J. M. KISHPAUGH

LIQUID MEASURING AND DISPENSING VESSEL

Filed March 9, 1922

Inventor:

JOHN M. KISHPAUGH.
BY Hazard & Miller
Attorneys.

UNITED STATES PATENT OFFICE.

JOHN M. KISHPAUGH, OF PASADENA, CALIFORNIA.

LIQUID MEASURING AND DISPENSING VESSEL.

Application filed March 9, 1922. Serial No. 542,281.

To all whom it may concern:

Be it known that I, JOHN M. KISHPAUGH, a citizen of the United States, residing at Pasadena, in the county of Los Angeles and 5 State of California, have invented new and useful Improvements in Liquid Measuring and Dispensing Vessels, of which the following is a specification.

My invention relates to vessels adapted 10 for use in the dispensing of liquids, and a purpose of my invention is the provision of a dispensing vessel by means of which liquid, such as oil or the like, can be dispensed in any predetermined quantity 15 whereby a saving in the liquid dispensed is effected, and the necessity of frequently refilling the vessel is eliminated.

Although I will describe only one form 20 of liquid measuring and dispensing vessel embodying my invention and point out the novel features thereof in claims, it is to be understood that various changes and modifications may be made herein without departing from the spirit and scope of such 25 claims.

In the accompanying drawings,

Figure 1 is a view showing in perspective one form of liquid measuring and dispensing vessel embodying my invention.

30 Fig. 2 is an enlarged top plan view of the vessel shown in Fig. 1.

Fig. 3 is an enlarged vertical sectional view of the vessel shown in the preceding views.

35 Fig. 4 is a transverse sectional view taken on the line 4—4 of Fig. 3.

Fig. 5 is a fragmentary sectional view showing a closure adapted for use in conjunction with the filling spout of the vessel.

40 Referring specifically to the drawings in which similar reference characters refer to similar parts, my invention, in its present embodiment, comprises a cylindrical body portion B with which is integrally formed 45 or suitably secured thereto a cylindrical sleeve S closed at its lower end by a wall 15. Fixed within the body B at regular spaced intervals are inclined partitions P which extend completely across the body 50 with their lower edges fixed to the sleeve S.

These partitions are provided with vent 55 openings 16 at corresponding points adjacent their upper ends, and all of these vent

openings are in registration with a filling spout F formed on the upper end of the 55 body B.

The sleeve S is adapted to receive a valve member V which is of tubular form and of such a diameter as to slidably fit within the sleeve. This member V is provided at 60 spaced intervals with ports 17, 18 and 19, and these ports are adapted to register with openings 20, 21 and 22, respectively, formed in the sleeve S at points adjacent the lower ends of the partitions P. The ports 17, 18 65 and 19 are of graduated lengths, the ports increasing in length from the lowermost to the uppermost as is clearly shown in Fig. 3. Adjacent the lower end of the lowermost partition P another opening 23 is provided 70 in the sleeve S, and this opening is adapted to be controlled by the lower end of the valve member V as will be more fully described hereinafter. The upper end of the valve member V is formed at intervals with 75 notches 24 which are numbered as shown, and these notches define the positions of the valve member when the ports 17, 18 and 19 are in registration with their correspond- 80 ing openings, as well as indicating the po- 80 sition of the member when its lower end is so disposed as to expose the opening 23. A latch 25 is mounted on the sleeve S and extends through a suitable opening so as to engage the several notches 24 for secur- 85 ing the valve member in any one of its several positions.

For manually actuating the valve mem- 90 ber V, an arm 26 is secured to the member adjacent its upper end so that with the hand gripping a handle 27, the index finger by engaging the arm 26 can lift the valve member to any desired position. The handle 27 is formed between the sleeve S and a partition 28 constituting a portion of the 95 filling spout F. This partition 28 is bent in such manner as to allow of the ready application of the hand to gripping position with respect to the handle 27, and it also allows of the arm 26 moving downwardly to 100 a position in which all the ports of the valve member are closed.

A flexible discharge spout D is secured at one end to the sleeve S and is in commu- 105 nication with the lower end of the sleeve through an opening 29. The free end of

the discharge spout is adapted to be sustained in upright position upon the vessel by means of a relatively small bracket 30 adapted to engage a hook 31 secured to the 5 sleeve S.

In practice, the body B of the vessel is preferably designed to contain a gallon of liquid when completely filled, and the partitions P are so arranged that the space 10 between any two adjacent partitions will accommodate a quart of liquid when completely filled. In the present instance I have shown four partitions, and these four partitions define four compartments from 15 which the passage of liquid is controlled by the valve member V.

In operation, the vessel is adapted to be filled through the filling spout F and as the liquid is introduced, the uppermost compartment is first filled whereupon the overflow passes through the vent opening 16 to the next compartment below and so on until all of the compartments are completely filled. It is to be understood that during the filling 25 operation, the valve member V is in its lowermost position so that all of the ports are out of registration with the sleeve openings so that the passage of the liquid from the compartments is prevented. However, 30 when it is desired to dispense the liquid from the uppermost compartment, the valve member V is lifted by exerting an upward pressure upon the arm 26 and until port 17 moves into registration with the opening 20. 35 In this position of the valve member the latch 25 engages within the first notch of the member which is numbered one. The liquid from the uppermost compartment can now flow downwardly through the valve member 40 and sleeve into the discharge spout D, and with the latter in lowered position with respect to the vessel, it will be clear that the liquid will gravitate from the spout. When dispensing the liquid from the second com- 45 partment, the valve member is lifted another notch thereby moving the port 18 into registration with the opening 21. The suc- 50 ceeding compartments may be emptied in a similar manner, with the liquid from the lowermost compartment passing through 55 the opening 23 when the valve member is in its uppermost position. When all of the compartments have been emptied, they can be readily refilled by moving the valve mem- 60 ber V to its lowermost position through exerting a pressure with the thumb down- 65 wardly upon the member so that all of the openings are now closed.

From the foregoing operation taken in 60 conjunction with the accompanying draw- 65 ings, it will be manifest that I have pro- 70 vided a liquid dispensing vessel by means of which liquid in predetermined quantities can be readily dispensed from the one and same 75 vessel. My invention is of special advantage

in the dispensing of oils at automobile supply stations, and in this adaptation the body of the vessel is designed to contain a gallon of oil with each compartment accom- 80 modating a quart of the liquid, so that 70 by a manipulation of the valve member V the oil can be successively dispensed from the several compartments. With a dispens- 85 ing vessel of this character, it will be clear that any quantity of oil up to a gallon can 75 be dispensed and without the necessity of the operator returning to the oil tank for the purpose of refilling the vessel as is necessary with the dispensing vessels heretofore proposed. 80

What I claim is:

1. A liquid dispensing and measuring vessel comprising a body, a sleeve sustained on the body, transverse inclined partitions arranged within the body at one side of the 85 sleeve to divide the latter into a plurality of compartments, a discharge spout communicating with said sleeve, a plurality of openings formed in said sleeve for effecting communication between the compartments and said discharge spout, and a valve member movable in the sleeve and having ports formed therein to control said openings. 90

2. A liquid dispensing and measuring vessel comprising a body, a sleeve sustained on the body, inclined partitions arranged within the body to divide the latter into a plurality of compartments, a discharge spout communicating with said sleeve, a plurality of openings formed in said sleeve 100 for effecting communication between the compartments and said discharge spout, and a valve member slideable within the sleeve and having ports of graduating sizes so arranged that as the member is moved longitudinally said openings will be successively exposed to allow of the successive discharge of liquid from the several compartments into said discharge spout. 105

3. A liquid dispensing and measuring vessel comprising a body, a sleeve sustained on the body, inclined partitions arranged within the body to divide the latter into a plurality of compartments, a discharge spout communicating with said sleeve, a plurality of openings formed in said sleeve 110 for effecting communication between the compartments and said discharge spout, a valve member slideable in said sleeve and having ports formed therein adapted to register with the openings of said compartments, notches formed in said member for indicating the position of the ports thereof, and a latch sustained on the body and adapt- 115 ed to engage within said notches for tempor- 120 rarily securing the member in any of its several positions. 125

4. A liquid dispensing and measuring vessel comprising a body divided into a plu- 130 rality of compartments, a valve member of

tubular form slidable from the top of the body to control the dispensing of liquid from any of the compartments, an element on top of the body adapted to be gripped for supporting the body and arranged to permit actuation of the valve member while gripping the element and releasable means for locking the valve member in any of the several dispensing positions which it is capable of occupying. In testimony whereof I have signed my name to this specification.

10

JOHN M. KISHPAUGH.
